INVENTOR.

UNITED STATES PATENT OFFICE.

JAMES D. GIBBS, OF LOUISVILLE, KENTUCKY, ASSIGNOR TO GIBBS-INMAN COMPANY,
OF LOUISVILLE, KENTUCKY.

CASH-CHECK.

1,084,143.

Specification of Letters Patent.

Patented Jan. 13, 1914.

Application filed December 3, 1909. Serial No. 531,273.

To all whom it may concern:

Be it known that I, JAMES D. GIBBS, of Louisville, Jefferson county, Kentucky, have invented new and useful Improvements in 5 Cash-Checks, of which the following is a specification.

In present forms of cash fare receipts, the stubs, after being detached from the passenger's receipt, are deposited in the 10 pocket or other receptacle carried by the conductor, the result being confusion of the numerical rotation, and often, the loss or defacement of some of them.

It is the object of my improvement to 15 overcome this troublesome practice by retaining the stubs intact in the cutter or manipulator until the conductor reaches the end of his run.

Another objection to the present form is 20 that the cutters are inconvenient in point of operation and liable to damage in the pocket and in handling by conductor. Furthermore, the relative parts of the cutter are not assembled in a manner conducive to 25 long wear.

These objections are entirely remedied by 30 my invention, which is fully set forth in the accompanying specification and drawing, similar characters of reference being used 35 to indicate corresponding parts in the several views.

Figure 1 is a general view of my improved cutter with a pad of tickets held in normal position to be executed to represent 35 various amounts of fare, and showing the stubs of some of the tickets from which the receipts have already been detached. Fig. 2 is an end view of the cutter and pad of tickets with stubs turned back in readiness 40 for the next operation. Fig. 3 is also an end view of the cutter and tickets, showing the severed stubs as they lie above the blades, and the whole enveloped in a leather cover. Fig. 4 is a front view of base-plate, showing 45 manner of attaching the swinging frame.

The cutter consists of a base-plate or holder A, having up-turned edges or rims c, d, a swinging frame B, the cutters D, E, 50 F, and the retaining strip G. Heretofore the cutter blades have been retained in position by a pin passing through a slot, in a manner which prevents turning back the stubs after being severed from the receipt

portions, whereby it is necessary to remove 55 the stub after each operation. Furthermore, the projecting parts are injurious to the pockets and, being exposed, are constantly liable to damage. To overcome these objections I form two arms B' B', on 60 the strip or frame B, carrying the cutter-blades, the extremities of which are curved and passed through the slots a a, in the rim c to form the hinges b b, whereby the cutter-blades are raised up after each severing 65 operation and the stubs turned back preparatory to the next operation. As a safe-guard, and further convenience to the conductor, I bind the slips or tickets in pads of suitable thickness by means, preferably, of flexible 70 glue or gum, i, but they may be bound by stitching, stapling or other means if preferred. It is well known that the flexibly padded sheets will not become detached unless they are drawn back beyond the line of 75 attachment, and to prevent this I bend a narrow width of the rim d, to substantially a right angle e, whereby the stubs are obstructed from being unintentionally detached. As a means of protection to both 80 the cutter and the pockets in which it is carried, I employ a suitable cover, J, preferably of leather, which is affixed to the base-plate A by means of a small brad or fastener, j, at either end, and this cover, when 85 open, in no wise interferes with the process of operation.

In practice, my improved cash check is handled as follows: A supply of tickets or slips sufficient for a given trip or run is installed in the holder, which is easily accomplished by merely raising the swinging frame, and when a receipt is to be given, the operator slides the several cutters back and forth by means of the thumb-pieces, f, 90 g, h, until they intersect the series of figures at the desired points, then while holding firmly the thumb-piece g, severs the ticket first from the top to the middle along the cutting edges, then from the bottom completing the separation. The portion H thus detached becomes a receipt for the fare collected and is handed to the passenger, after which the swing-frame B, with its accompanying cutters, is raised, the stub, I, turned back and the cutters dropped back to their normal position. At the conclusion of his trip the conductor removes the pad of 100 105

slips from the holder, detaches all the stubs from which receipts have been cut and disposes of them according to his instructions.

Having thus described my invention, what I claim is:

- 5 1. A ticket case embodying a holder adapted to receive a pad of tickets flexibly united along one edge, a frame hinged to the holder at the edge opposite the position of the uniting of the tickets and carrying cutters, and a strip extending over the holder at the edge opposite the hinging of the frame adapted to permit tickets being turned backwardly a limited distance but to prevent them being turned backwardly far enough to be disengaged from the pad.
- 10 2. In a ticket case, the combination with a holder adapted to receive a pad of tickets flexibly united along one edge, of a severing frame pivoted to one edge of the holder and a strip rigidly carried by the holder extending over the position of the united edge of the tickets and positioned to permit tickets being turned backwardly a limited distance but to prevent them from being bent backwardly to such a degree as to sever tickets from the pad.
- 15 3. A ticket case embodying a holder adapted to receive a pad of tickets flexibly united along one edge, a frame hinged to

the case at the edge opposite the position of the uniting of the tickets and carrying cutters extending toward the hinge and of different widths and separably movable, and a strip extending over the holder at the edge 35 opposite the hinging of the frame adapted to permit tickets being turned backwardly a limited distance but to prevent them being turned backwardly far enough to be disengaged from the pad.

4. A ticket case embodying a holder adapted to receive a pad of tickets flexibly united along one edge, a frame hinged to the holder at the edge opposite the position of the uniting of the tickets and having a 45 strip extending along the edge adjacent such position, cutters carried by the last mentioned strip and independently movable, such cutters being of different widths and extending different distances toward the 50 hinge, and a strip extending over the holder at the edge opposite the hinging of the frame adapted to permit tickets being turned backwardly a limited distance but to prevent them being turned backwardly far 55 enough to be disengaged from the pad.

JAMES D. GIBBS.
